UNITED STATES PATENT OFFICE.

MAX MEYBERG, OF LOS ANGELES, CALIFORNIA.

KEYLESS SWITCH-SOCKET FOR INCANDESCENT LAMPS.

SPECIFICATION forming part of Letters Patent No. 622,188, dated March 28, 1899.

Application filed November 14, 1898. Serial No. 696,434. (No model.)

To all whom it may concern:

Be it known that I, MAX MEYBERG, a citizen of the United States, residing at Los Angeles, in the county of Los Angeles and State 5 of California, have invented a new and useful Keyless Switch-Socket for Incandescent Lamps, of which the following is a specification.

The particular object of my invention is to 10 provide means whereby by grasping the bulb of the lamp, which is usually the lowest portion thereof, the switch which turns the current on and off from the lamp may be operated.

A further object of my invention is to 15 provide a neat and artistic metallic covering for the switch mechanism and for the metallic jacket which incloses the upper end of the lamp-bulb and through which the circuit of the lamp is maintained and to insulate such 20 covering from the electric current without the use of the insulated lining commonly used in such covering. By my improved sleeve I conceal the metallic jacket of the lamp from view and prevent accidental contact with any 25 live portion of the lamp.

A further object of my invention is to dispense with one of the insulating-plates commonly used in key switch-sockets and to do away with the expensive and complicated 30 switch mechanism heretofore employed for making and breaking the circuit.

My invention comprises the various features of construction and combinations of parts hereinafter fully set forth and claimed, 35 whereby I accomplish the objects hereinbefore specified.

The accompanying drawings illustrate my invention.

Figure 1 is a fragmental side elevation of a 40 lamp-socket and lamp provided with my invention and showing the switch closed to form the electrical connection between the lamp and the direct and return wires. Fig. 2 is a like view showing the switch open. Fig. 3 is 45 a fragmental view showing the insulating-plate with the contact-point and the stem-socket secured thereto and the lamp having its stem provided with the stud. Fig. 4 is a fragmental sectional view showing a lamp- 50 insulating plate provided with a solid stem to afford a firm support for the stud. Fig. 5 is a view of a modified form of switch device

adapted to be operated by the lamp. Fig. 6 shows another form.

In the drawings, A represents a socket member or cap, and B represents the ordinary insulating plug or plate, of porcelain or other suitable insulating material. To the center of this plug is secured a sleeve or stem-socket C, which forms one contact-point and is provided with a spiral cam-slot c, having two stud-seats c' c'', respectively. As shown in the drawings, one stud-seat is arranged above the other. A second contact-point D is also secured to the insulating plug or plate, and the 60 direct and return wires E F are connected one with the socket C and the other with the contact-point.

G is the lamp, which has its stem g provided with a stud g', secured to the stem and 70 adapted to slide in the cam-slot in the socket and to seat in either the upper or the lower stud-seats, as will hereinafter be fully explained. This stud g' may be secured to a sleeve g'', which may be slipped upon the stem 75 of an ordinary incandescent lamp and soldered thereto, as indicated in Figs. 3 and 5, so as to adapt any ordinary incandescent lamp for use with my improved socket.

H is a sleeve which is of a size suitable to fit 80 around the outside of the cap A. The top edge of the sleeve is preferably curled or turned slightly inward, so as to engage with a similar curved or outward-turned portion on the lower edge of the cap and prevent the 85 sleeve from slipping off. Screws h h' are inserted through the cap and into the insulating-plug B, so that their heads will project just above the edge of the sleeve and prevent the sleeve from being moved upward until 90 after the screws have been removed. In this manner the screws not only hold the sleeve and cap together, but they hold the plug within the cap, thus simplifying the construction of the socket very materially.

The inturned or curled edges of the parts are of course formed before they are assembled and simply fit into each other when the parts are in position, as is clearly indicated in Figs. 1 and 2. By removing the screws h 100 h' the sleeve H may be slipped back over the cap A and free access had to the socket.

In Fig. 4 I have shown a fragment of a lamp provided with a stem G', which is formed of

a single piece of metal, preferably brass, bent at its lower end to form a foot G'' , which is secured to the under face of the porcelain cap-plate of the lamp, while the stem projects 5 through the plate and is provided with a minute hole G''' , into which fits the upper end of one of the lamp-wires. This gives a firm support for the stud g' , which is not afforded by the ordinary stem unless the sleeve g'' is 10 used.

In order to effectually cover all live portions of the lamp, so that by no possible means can a shock be received while handling the lamp when the current is on, I make this 15 sleeve H of a length sufficient to extend entirely below the metallic covering or jacket I upon the top of the lamp and to engage with the glass bulb I' of the lamp entirely below such jacket. The lower end of the sleeve may 20 be turned slightly inward, as shown in the drawings, and spring-tongues h'' may be provided to grasp between them the upper end or neck of the glass bulb and to yield to accommodate themselves to the shape of the 25 lamp and to allow the globe to be reciprocated back and forth in the socket-sleeve without permitting it to become loose and to rattle. This construction causes the sleeve to contact with the lamp only at one point—that is, in a 30 circle around the neck of the lamp—the remaining portion of the neck being out of contact with the sleeve and therefore unsupported thereby. As the neck of the lamp is usually smooth, the making of the sleeve 35 larger than the upper portion of the neck, except below the metal jacket or covering I , unless prevented would permit of the neck being canted over to one side or the other by the accidental movement of the bulb until 40 the covering would come in electrical contact with the sleeve. To prevent this, the stem or other connection at the top of the neck of the lamp will engage with the socket on the insulating plate or plug B , and thereby hold 45 the stem axially within the sleeve at all times when they are in operative position. As the neck of the ordinary lamp usually begins to expand just below the metallic jacket to form the bulb, it will be seen that the pressure of 50 the tongues, which may be of any desired length, upon the inclined wall of the lamp will have a tendency to press the bulb out of the socket, and thereby cause the pin g' to always bear against the wall of the slot C and 55 prevent its movement or rattling. In addition to these advantages the pressure of the spring-tongues against the lamp can be made sufficiently strong to normally press the lamp outward with such force as to prevent the 60 neck of the bulb from accidentally slipping down into the sleeve if the lamp is used in an upright instead of pendent position, as in the footlights, where the jar upon the stage might cause a movement downward of the bulb and make a contact between the points 65 when it was not desired that the lamps should be lighted.

In practical operation, the parts being held as shown in Fig. 3 of the drawings, the lamp is raised and turned to the right and the stud g' 70 enters the slot c and is carried over the rise or incline c'' into the lower stud-seat c' . When the stud is in this position, the lamp is not elevated sufficiently to bring the metallic sleeve I into contact with the point D , so that 75 the switch is open and the current does not flow through the lamp. When it is desired to light the lamp, it is grasped by the bulb and pushed upward, thus bringing the contact-point D into contact with the metallic jacket 80 I , thus closing the switch and allowing the current to flow through the lamp. The lamp is then turned toward the right, thus carrying the stud g' into the stud-seat c'' and holds the switch closed until it is desired to extinguish 85 the light. To do this, the lamp is turned slightly to the left, thus withdrawing the stud from the seat c'' , and the lamp is slightly withdrawn or lowered to seat the stud in the seat 90 c' and to withdraw the jacket I from its contact with the contact-point D .

As shown in Fig. 5, the stud-seats $c' c''$ are in the same horizontal plane, and a point I'' , which is formed integrally with or secured to the jacket I , is adapted to be brought into engagement with the point D when the lamp is rotated or turned to bring the stud g' into the seat c'' and to carry it out of engagement therewith when turned to seat the stud in the seat c' . 100

It will be noted that the sleeve H contacts only with the insulated cap-piece A at its upper end and with the glass bulb of the lamp at its lower end, so that all live portions of the lamp are inclosed and protected within an 105 insulated covering, and it becomes impossible to accidentally receive a shock.

By my invention but a single insulating-plate is needed in the socket instead of the two heretofore employed, and, furthermore, 110 I shorten the socket and dispense with the complicated and expensive switch mechanism heretofore used and employ the very fewest possible number of parts in my improved socket. 115

By removing the screws $h h'$ the sleeve H , as shown in Fig. 1, may be slipped upward along the supporting-stem, thus exposing the entire switch mechanism to view without removing the lamp from the socket. 120

In Fig. 6 I have shown the sleeve C' internally screw-threaded and the stem g of the lamp provided with an externally - screw-threaded sleeve g''' , which screws into the sleeve or socket to carry the jacket I of the 125 lamp into and out of contact with the contact-point D , thus to open and close the switch. Other forms may be devised without departing from the spirit of my invention.

Now, having described my invention, what 130 I claim as new, and desire to secure by Letters Patent, is—

1. In a lamp-socket, the combination, with a plate; of a sleeve secured thereto, said sleeve

being provided with spring-tongues for engaging with the sloping wall of the lamp to normally press the same outward; and interlocking means for holding the neck of the lamp axially within the sleeve and permitting a partial rotation thereof to bring it to a dormant or active position.

2. In a lamp-socket, the combination, with a plate; of a sleeve movably secured thereto; said sleeve being provided with spring-tongues for engaging with the sloping wall of the lamp to normally press the same outward; and means for holding the neck of the lamp axially within the sleeve, and permitting a partial rotation thereof, to bring it to a dormant or active position.

3. In a lamp-socket, the combination, with a plate; of a cap-piece thereon, the lower edge of which is turned outward; a sleeve over the cap-piece, the upper edge of which is turned inward; and screws through the cap-piece into the plate above the edge of the sleeve.

4. The combination with a lamp-socket; of a lamp secured thereto, the neck of the lamp being provided with a metallic jacket forming one of the contact-points; a sleeve secured upon the socket extending down over the jacket at a slight distance therefrom; spring-tongues formed upon the end of the sleeve adapted to bear upon the sloping neck of the lamp; and means for holding the neck of the lamp axially within the sleeve and permitting a rotation thereof, substantially as described.

5. The combination with a lamp-socket; of a lamp detachably secured thereto, the socket and the neck of the lamp being provided with interlocking projections permitting endwise and rotary movement of the parts; and a sleeve carried by the socket provided with spring-tongues, which, bearing upon the sloping wall of the lamp, tend to rotate and urge the same outward and thereby to hold the locking projections in firm contact.

6. The combination, with a lamp-socket, one terminal of which forms a central projection, and the other terminal projects at a distance therefrom; of a lamp secured thereto in such manner as to be rendered dormant or

active by a longitudinal movement thereof, the neck of the lamp being provided with a central projection forming one terminal, and with a metallic jacket forming the other terminal, said jacket being in position to engage the second-mentioned projection of the socket only when the lamp is in its active position.

7. The combination with a lamp-socket, one terminal of which forms a centrally-located slotted socket, and the other terminal is located at a distance therefrom; of a lamp rotatably secured to the socket, one terminal of which forms a central stem provided with a stud to engage with the slotted socket, and the other terminal forms a metallic jacket in position to engage with the projection of the lamp-socket only when the lamp is in its active position.

8. The combination, with a lamp-socket, one terminal of which forms a centrally-located socket and the other one forms a projection at a distance therefrom, said socket being provided with a spiral slot having two stud-seats in different horizontal planes; of a lamp rotatably secured to the socket, one terminal of which forms a central stem provided with a stud, and the other terminal forms a metallic jacket in position to engage with the projection in the lamp-socket only when the lamp is in its active position.

9. The combination, with a lamp-socket, one terminal of which forms a centrally-located socket, and the other one forms a projection, at a distance therefrom; said socket being provided with a spiral slot; of a lamp rotatably secured thereto, one terminal of which forms a central stem provided with a stud and the other terminal forms a metallic jacket in position to engage the projection in the lamp-socket, only when the lamp is in its active position, said lamp-socket being provided with a tongued sleeve of a greater length than the width of the jacket.
